UNITED STATES PATENT OFFICE

CHARLES B. ULRICH, OF JAMESTOWN, NEW YORK, ASSIGNOR TO ART METAL CONSTRUCTION COMPANY, OF JAMESTOWN, NEW YORK

FLOORING

Application filed June 1, 1929. Serial No. 367,647.

This invention relates to flooring made mainly of metal and particularly to flooring of this kind which is used to form galleries or elevated walks in connection with shelving for books, records, merchandise or the like.

The objects of this invention are to form flooring of this kind of sheet metal and built in sections or units adapted to be secured together to form the flooring; also to construct the sections or units with edge portions bent to form reinforcing flanges for reinforcing the units and to facilitate securing the units together; also to form sheet metal sections or units of this kind having the edges thereof bent to form curbs or dust guards and also to reinforce and strengthen the flooring; also to provide means of improved construction for reinforcing the corners of sections of the flooring; also to provide means of improved construction for reinforcing or stiffening the intermediate portions of the flooring; also to provide flooring of this kind which is built or constructed in sections which can easily be secured together and which reinforce each other when secured together; and also to improve flooring of this kind in other respects hereinafter specified.

In the accompanying drawings:

Fig. 1 is a fragmentary sectional elevation of a length of flooring embodying this invention and showing the same applied to shelving and to a wall of a building;

Fig. 2 is a transverse fragmentary sectional elevation of shelving having flooring secured thereto, taken on line 2-2, Fig. 1;

Fig. 3 is a fragmentary sectional plan view of the shelving on an enlarged scale showing the plan view of the flooring;

Fig. 4 is a transverse fragmentary sectional elevation thereof on line 4-4 of Fig. 3 on a still larger scale;

Fig. 5 is a similar transverse sectional elevation of a section of flooring of modified construction;

Fig. 6 is a plan view, partly in section, of one of the flooring units showing the manner of securing the same to adjacent units and of

supporting the same from shelving or other structures;

Fig. 7 is a sectional elevation, on a reduced scale, of flooring mounted in a different manner, from shelving or other upright supports;

Fig. 8 is a fragmentary transverse sectional view, on an enlarged scale, on line 8-8 of Fig. 7;

Fig. 9 is a perspective view of a corner of a unit of flooring showing the means employed for aligning the dust guard or curbing; and

Fig. 10 is a fragmentary bottom plan view of a corner of a unit of flooring showing a supporting member of another form secured thereto.

The flooring embodying this invention is shown in the accompanying drawings as applied to shelving, but it will be understood that my improved flooring may be used for other purposes, if desired. In Figs. 1 to 3, A represents a wall of a building and B B represents shelving which may be of any usual or suitable construction.

The flooring embodying this invention is built in sections or units which are so constructed as to be readily secured to each other to form flooring of any desired dimensions. The sections or units are made either entirely or mainly of sheet metal, which is bent or formed at the edge portions thereof in such a manner as to reinforce the sections or units and to enable them to be secured together below the tread portions thereof. By constructing flooring in this manner, a strong and rigid floor results, since the abutting flanged edges of the units constitute the equivalents of reinforcing beams or joists for the flooring.

Flooring of this kind is consequently light in weight and strong and the units can be constructed at a factory in convenient sizes and shipped to the place where they are to be installed in condition to be readily and quickly assembled.

The units or sections may be of any suitable or desired construction, those shown in the drawings each including a tread portion 15 which may be substantially flat or other-

wise formed and the edges of each section are bent to form reinforcing flanges to stiffen the flooring to enable the same to support the necessary loads. It is also desirable that the edges of the assembled floor be provided with dust guards, and in accordance with my invention, these dust guards are formed by bending one or two of the sides or edge portions of a section, which are to constitute edges of the flooring, upwardly to form dust guards. These dust guards or curbs are preferably inclined as indicated at 16, but if desired, the dust guards may extend vertically upwardly from the tread portions 15, as indicated at 14 in Figs. 1 and 3. The inclined dust guards have some advantages, for example, that they can be easily aligned, as will be hereinafter more fully explained, and also make it easier to keep the flooring clean, but difficulties would arise to form a finished appearing corner at the intersection of two of these dust guards. To overcome this difficulty, I form the flooring in such a manner that at the intersection of two dust guards, one of the dust guards is of the vertical type 14 as is shown in Fig. 3. It is then merely necessary to cut the end of the vertical dust guard at an angle corresponding to the angle of the inclined dust guard 16, whereupon a correctly fitting corner is formed. Dust guards or curbing of other forms may, however, be employed if desired.

These dust guards reinforce or stiffen the flat or tread portion 15 of the flooring and in order to further reinforce these edges of the sections, downwardly extending flanges 17 are formed which extend from the upper edges of the dust guards 14 and 16 downwardly, and if desired, the lower ends of these upright reinforcing flanges may be provided at their lower edges with flanges 18 which extend parallel with the tread portion 15 and preferably inwardly or toward the middle portions of the sections. The dust guards and the flanges 17 and 18 form a structural section, which is made by bending integral parts of a sheet or plate of metal, and which are preferably formed integral with the tread portion 15 and reinforce the same to enable the sections of the flooring to carry the loads to which they may be subjected.

Those sides of the sections which are not provided with dust guards, preferably have their edge portions bent to form downwardly extending flanges 20, the lower ends of which may also terminate in inwardly extending flanges or parts 21, which extend parallel to and underneath the tread portion 15 of the floor section. These integral parts of the sections of the flooring also reinforce the same and may also be secured to corresponding portions of adjacent sections or units of the flooring.

After the edge portions of a section of flooring have been bent into the form described, corner pieces are preferably secured to the downwardly extending flanges of the units of the floor. These corner pieces may be of any suitable or desired form, those shown as indicated at 24, being made of sheet metal bent into angular shape. These corner pieces are placed with their two legs in contact with adjacent parts of the downwardly extending flanges 17 and 20 and are then spot welded or otherwise rigidly secured to the flanges.

These corner pieces form rigid connections between the upright flanges and thus form a rigid reinforcing structure, holding the flanges 17 and 20 in their upright positions in which they will most effectively resist the strains to which the flooring is subjected, and also causing each flange to assist in holding an adjacent flange or flanges in their upright positions.

When the flooring is used between two shelves or cases B as shown in Figs. 1 and 3, the sections of flooring may be provided with dust guards 14 or 16 at opposite edges thereof. The other two sides of the flooring are provided with downwardly extending flanges 20 which may be secured to corresponding flanges of an adjacent section of the flooring so that the tread portions 15 form a continuous surface.

In order to reinforce the intermediate parts of the tread portions of the sections or units between the sides thereof, reinforcing beams or members of any suitable structure are preferably secured to the sections. In the particular construction shown, these reinforcing members are also made of sheet metal bent to form structural shapes having one or more upright webs for resisting downward stresses. In the construction shown in Figs. 2, 4, 6 and 7, these reinforcing members are in the form of channel or U-shaped beams 28, each of which has a pair of upright webs connected at their lower ends by a base web 30, and the upper edges of the upright webs are bent outwardly to form flanges 29 which may be welded or otherwise secured to the tread portion 15 of the flooring. The base web 30 which connects the upright webs of each beam preferably rests at its outer ends either on the inwardly turned flanges 21 or 18 of a floor section or unit. In the construction shown the beams 28 rest on the flanges 21 with the ends of their upright webs abutting against the upright flanges 20 of the sections, so that these flanges of adjacent sections are braced against inward deflection, as shown in Fig. 6.

In this manner the intermediate parts of the tread portions of the sections are reinforced and the stresses transmitted to the beams are taken in part by the webs 21, so

that a thoroughly rigid structure results. It will be obvious that reinforcing beams or members or other construction may be employed, if desired.

For example, in Fig. 5, beams 33 of Z-shaped cross section are provided, each of which has an upright flange terminating in horizontal flanges at the upper and lower edges thereof, the upper flange being welded or otherwise secured to the under face of the tread portion 15. When this construction is employed, the lower flanges of the reinforcing beams 33 may be utilized for fastening a ceiling plate 35 thereto. In the construction shown, the ceiling plate has a series of lips or hooks 34 secured to the upper face thereof, which lips may hook over a lower flange 18 of the lower flanges of the reinforcing beams 33 as clearly shown in Fig. 5, the ceiling member then being rigidly secured against unhooking by means of one or more screws 36, passing through the ceiling plate and a flange 18 or 21.

The flooring may be supported in any suitable or desired manner and several different types of supports for the flooring are shown in the drawings. For example, in Figs. 1 and 3 the edge of the flooring is supported from the wall A by means of a continuous angle bar 37, one flange of which is secured to the wall A in parallel relation thereto, and the other flange of which extends outwardly from the wall and supports the adjacent edge of the flooring. The flooring shown in Figs. 1 and 2 is supported from the shelving B by means of short lengths of angle bars 38, having their upright flanges secured to the shelving and a horizontal flange extending outwardly. In this construction only the corners of the sections of flooring are supported on the short angle bars 38.

When it is desired to secure the flooring to upright walls or partitions of shelving or similar structures, a very simple and efficient supporting means for the flooring may be provided as is clearly shown in Figs. 3, 4, 6 and 10. In this construction each section of the flooring is provided at the corners thereof with an integral supporting member which includes an outwardly extending vertical web or plate 40 having its outer end provided with apertures to receive bolts or screws 41. These bolts or screws connect the web or plate 40 with an upright wall or partition 42 of shelving or other structure. The plate 40 terminates at its inner end in an upright flange 44, which extends lengthwise of the adjacent longitudinal flange or edge of the flooring and which in turn is formed integral with a bottom flange or plate 45. The bottom flange or plate 45 is made of sufficient size to overlap the portions of two adjacent ends of the bottom flanges 18 and 21, and a bolt

or screw 47 passes through the bottom plate 45 and the bottom flange 21. Another bolt or other fastening device 48 preferably passes through holes in the upright flange 44 and the adjacent flange 17 of a section of flooring. Consequently, by the use of only two fastening devices or bolts, the supporting member can be rigidly secured to a section or unit of flooring, the webs or portions 44 and 45 of the supporting device being formed to carry the greater portion of the weight of the flooring independently of the bolts or fastening devices 47 and 48. These fastening devices are preferably arranged as clearly shown in Fig. 6 so that the upright plates or walls 42 of the structure to which the supporting members are secured are spaced between two plates 40 of adjacent supporting members, so that the bolts or fastening devices 41 serve to support the adjacent corners of two different units or sections of the flooring.

In the particular construction shown in Figs. 7 and 8, the flooring is supported on a plurality of upright plates or beams 50, the ends of which are secured to suitable upright supports 51 of the shelving or other structure. In this case the adjacent sections of flooring are merely abutted against the opposite faces of the plates or beams 50 as shown in Fig. 8 and bolts or other fastening devices 52 pass through the upright flanges 20 and the beams 50 thus securely hold the sections of flooring between adjacent beams. The upper edges of the beams preferably extend flush with the upper faces of the tread portions 15 of the flooring. When plates or beams of this kind are used between two units, the dust guards 16 and the upright flanges 17 thereof are formed in such a manner that they extend beyond the end flanges 20 of the sections, and this can easily be done by cutting the sheet metal from which the flooring sections are made accordingly. Preferably, these parts are made to extend beyond the flanges 20 to distances equal to half the thickness of the plates or beams 50 so that the ends of the dust guards will abut and leave no gaps, see Fig. 8.

The various supports for the flooring are illustrated merely by way of example and it will be obvious that other means for supporting the flooring may be devised.

When the flooring is positioned in place and supported in any desired manner from a structure, it is desirable to maintain the dust guards or curbing in correct alignment. This affords no difficulty in connection with the curbing 14 shown in Figs. 1 and 3, but with the inclined dust guards 16, additional means are preferably employed for maintaining these dust guards of the adjacent sections in alignment. In the construction illustrated for this pur-

pose, see particularly Figs. 4 and 9, aligning plates 55 are employed which are of such width as to fit comparatively tightly within the dust guards between the upper portion of the curbing and the upper edges of the corner plates 24.

These plates are of sufficient length to extend a short distance into the space between the inclined dust guards 16 and the upright reinforcing flanges 17 and it will be obvious that when two sections are secured together, the aligning plates 55 maintain the dust guards in their correct relations. These aligning plates also hold the adjacent portions of the flanges 17 in their correct upright positions in which they offer the greatest resistance to any strains to which the flooring may be subjected.

The flooring described adapts itself well for the support of lighting fixtures on the lower surface thereof. For example, the end flanges 20 of adjacent sections may be apertured as shown at 60 in Fig. 5 and a conduit 61 as shown in Fig. 4 may pass through these apertures. Suitable electric lights 62 may be mounted on the conduit 61 and if desired reflectors 63 may also be supported therefrom. This arrangement has the advantage that the lighting fixtures are mainly located within the flooring where they are not in the way and not apt to be struck. This affords the maximum amount of clear headroom below the flooring. When ceiling plates are used as shown in Fig. 5, openings (not shown) may be provided in these plates for the lighting devices.

The flooring described has the advantage that it is of very much lighter weight than other flooring heretofore used for the same purpose, and yet of sufficient strength to support the necessary loads. By forming the flooring of sheet metal and in sections, the two abutting flanges 20, which are secured together by bolts or other securing means 51, form structural shapes which not only facilitate the securing together of adjacent sections of flooring but also act as sills or flooring supporting beams for the entire flooring.

Consequently, the structure is especially rigid and each of the two adjacent flanges 20 prevents the other flange from buckling, thus greatly reinforcing the flooring without increasing the weight thereof. The flooring is so constructed that the sections can be formed and built up in a factory and when they are installed it is merely necessary to secure these sections together and secure them to shelving or other structures by means of bolts.

The tread portions 15 of the flooring may be provided with any desired covering, for example, the tread surfaces may be coated

with an asphalt paint, which prevents slipping on the flooring.

Claims:

1. Flooring formed of sections each of which includes a tread portion having an edge thereof bent upwardly to form an integral dust guard and a reinforcing flange extending downwardly from the upper edge of said dust guard, said flange having its lower edge portions bent in a direction substantially parallel with said tread, other sides of said tread having their edges bent to form downwardly extending flanges for attachment to corresponding flanges of adjacent sections, and said flanges having their lower edge portions bent substantially parallel with said tread portions to reinforce the flanges.

2. Sheet metal flooring formed in sections, each section including a tread portion having an edge thereof bent upwardly to form a dust guard and then downwardly to form a reinforcing flange, other sides of said tread portion having their edges bent downwardly to reinforce the tread portion and to be secured to the downwardly extending flanges of adjacent sections, corner pieces secured to and connecting the adjacent ends of downwardly extending flanges at the corners of said sections, the dust guard of adjacent sections being arranged in alignment, and a bar fitted within said dust guard between the top thereof and a corner piece and extending into a similar relation to a dust guard of an adjacent section for maintaining the adjacent ends of the dust guards in alignment.

3. Flooring including sections made of sheet metal and each having a tread portion, a dust guard formed on a side of the tread portion and including an inclined flange extending upwardly from the tread portion, and other sections having a dust guard extending vertically upward from said tread portion, the end of the vertical dust guard extending across and closing the end of the inclined dust guard of an adjacent section.

4. Flooring formed of sheet metal and having a horizontal tread member, and an edge member including an inclined portion extending upwardly and outwardly from said tread portion and a portion depending from the edge of said inclined portion, whereby when said edge member is subjected to outward lateral strain, said inclined portion is placed under tension and acts to prevent deformation of the edge member of the flooring.

5. Flooring made in sections, each of which includes a horizontal tread member and an edge member including an inclined portion extending upwardly and outwardly from said tread portion and having a reinforcing depending portion extending from

the edge thereof, whereby, when said edge member is subjected to outward lateral strain, said inclined portion is placed under tension and acts to prevent deformation of the edge member, and other sides of each section having depending reinforcing members for attachment to corresponding members of other sections, and means for rigidly attaching said members together.

10 6. Flooring formed of sheet metal and including a horizontal tread member and opposite side members each including an upwardly and outwardly inclined bracing portion, an upright flange depending therefrom and extending below said tread member, and each of said upright flanges having its lower edge bent inwardly below said tread member towards the other flange, whereby said side members form combined dust guards 15 and reinforcing members which act to stiffen said flooring and also prevent deformation of the edges thereof.

7. Flooring including a horizontal tread member, and an edge member including a flange bent upwardly at an obtuse angle to said tread portion to form a dust guard extending above the level of the tread portion, and a reinforcing portion including a web arranged in a substantially upright plane 20 and extending downwardly from the upper edge of said flange, said flange acting under tension against lateral strains upon said edge portion.
